UNITED STATES PATENT OFFICE

ALFRED REHM AND EDGAR SACHS, OF STUTTGART, GERMANY, ASSIGNEES TO ROBERT BOSCH AKTIENGESELLSCHAFT, OF STUTTGART, GERMANY

CURLING TONGS

Application filed April 19, 1929, Serial No. 356,425, and in Germany October 6, 1928.

The present invention relates to electrical heating elements and particularly to electrical heating elements for curling tongs.

When a heating element is mounted within 5 and insulated from a housing such as an arm of an electric curling tong which is not very much larger than the element itself the temperature drop between the heating element and the outer surface of the insulation depends largely upon the type of insulating 10 material employed.

The object of this invention is to provide a heating element and insulating means for said element which will produce a minimum 15 temperature drop.

To obtain this object a heating element is according to the invention, inserted in a glass tube having at least one U-bend therein.

Glass, similarly to any electrical insulator, 20 is a poor thermal conductor, but allows radiating heat to pass through. Consequently even when its outer wall is at a comparatively high temperature the inner wall of the glass tube is still far below its melting point.

25 Two forms of construction of the invention are shown by way of example in the drawings in which:—

Figure 1 is a view of a heating element, partly in section.

30 Figure 2 is a cross-section on a larger scale through a round curling tong arm with a heating element as shown in Figure 1 inserted therein.

Figure 3 is a cross-section on a larger scale 35 through a crescent-shaped curling tong arm with a heating element as shown in Figure 1 inserted therein.

Figure 4 is a view of the second form of heating element and

40 Figure 5 is a cross-section on a large scale through a double curved heating tong arm with a resistance as shown in Figure 4 inserted therein.

In the construction shown in Figure 1-3 an 45 electrical heating wire 2 is inserted in a U-shaped tube 1 of ordinary glass. The two ends of the arm of the glass tube are sealed by a common glass seal 3 in which the two leads 4 to the heating wire 2 are fused. The 50 surface of the glass seal 3 at which the two

wires 4 emerge is provided with two extensions or mounting elements 5 over which an insulating tube (not shown) can be placed to protect the wires 4.

The glass tube 1 may be fitted into a round 55 sheet metal sleeve 6 (Figure 2) or into a crescent-shaped sheet metal sleeve 7 (Figure 3) and is secured therein by cement 8 made from graphite and water-glass with addition of water. This cement is a good conductor 60 of heat and adheres well to glass and sheet metal without attacking the same. The sleeves 6 and 7 are inserted in suitable hollow arms 9 and 10 of curling tongs. The mechanical strength of the heating element is 65 increased by the insertion in the sheet metal sleeve and is thereby at the same time given a definite shape which facilitates replacement.

In producing the heating element the helically wound heating wire 2 is first inserted, 70 with the two wires soldered to it, in a glass tube at least approximately straight, the melting point of which is below the melting point of the heating wire. The glass tube is then heated at its centre and bent into the U- 75 shape. The glass element 3 is then fused on to the open end of the glass tube and the two wires 4 nipped it so as to form the two extensions 5.

If desired the glass tube may also be bent 80 into a multiple U. A sinuous glass tube 11 is shown in Fig. 4. Instead of cementing the glass tube in its sheath, it can also be cast in with a substance having high thermal conductivity. In the form of construction 85 shown in Fig. 5 the glass tube 11 of difficultly fusible glass is cast-in with aluminum 12 and the casting is inserted in a double curved hollow curling-tong arm 13. Aluminum is a good conductor of heat and can easily be cast 90 in any desired shape. If desired the casting 12 can also be directly constructed as a curling-tong arm so that the sheath or sleeve element 13 can be omitted.

We claim:

1. An electrically heated curling tong including a hollow tong element, a plug similar in cross-sectional shape to the shape of the tong element located within said tong element, a glass tube having at least one U-bend 100

therein within said tong element and secured in the material of said plug, a heating wire within said glass tube and projecting beyond the ends thereof, and sealing means at each end of said glass tube.

5 2. An electrically heated curling tong including a hollow tong element, a sleeve within said tong element, filling material embedded in said sleeve to form a plug, a glass tube having at least one U-bend therein within said tong element and secured in said filling material, a heating wire within said glass tube and projecting beyond the ends thereof, and sealing means at each end of said glass tube.

10 15 3. An electrically heated curling tong including a hollow tong element, a sleeve within said tong, cement of high thermal conductivity embedded in said sleeve to form a plug, a glass tube having at least one U-bend therein within said tong element and secured in said cement, a heating wire within said glass tube and projecting beyond the ends thereof, and sealing means at each end of said glass tube.

20 25 4. An electrically heated curling tong including a hollow tong element, a sleeve within said tong, cement formed of graphite, water glass and water embedded in said sleeve to form a plug, a glass tube having at least one U-bend therein within said tong element and secured in said cement, a heating wire within said glass tube and projecting beyond the ends thereof, and sealing means at each end of said glass tube.

30 35 5. An electrically heated curling tong including a hollow tong element, a plug similar in cross-sectional shape to the shape of the tong element located within said tong element, a glass tube having at least one U-bend therein within said tong element and secured in the material of said plug, a coiled heating wire within said glass tube and projecting beyond the ends thereof, and sealing means at each end of said glass tube.

40 45 6. An electrically heated curling tong including a metal tong element, a glass tube having at least one U-bend therein within said tong element and a heating wire within said glass tube and projecting beyond the ends thereof.

50 In testimony whereof we have hereunto affixed our signatures.
